UNITED STATES PATENT OFFICE.

ERNST W. NELSON, OF ONG, NEBRASKA.

EGG TRAY.

Application filed May 26, 1926. Serial No. 111,781.

This invention relates to incubator trays and pertains particularly to an egg turning tray.

The primary object of this invention is the provision, in a manner as hereinafter set forth, of an egg turner tray having a slat revolving mechanism of improved structure, easily and quickly applied or removed, and adapted to be adjusted to keep the working parts always in close positive engagement.

Another object of the invention is the provision, in a manner as hereinafter set forth, of an incubator egg turner tray having a new and novel roller mounting therefor.

The invention has for another and final object, the provision in a manner as herein-after set forth, of an incubator egg turner tray of light but strong and durable construction, adapted to smoothly and easily turn the eggs placed therein without danger of injury to the same, and comparatively inexpensive to manufacture and set up.

The invention will be best understood from a consideration of the following detailed description taken in connection with the accompanying drawings forming a part of this specification, with the understanding that the invention is not confined to any strict conformity with the showing of the drawings but may be changed and modified so long as such changes and modifications mark no material departure from the salient features of the invention as expressed in the appended claim.

In the drawings:

Figure 1 shows the tray embodying this invention in top plan view.

Figure 2 is a longitudinal sectional view taken upon the line 2—2 of Figure 1.

Figure 3 is a bottom plan view of the tray and,

Figure 4 is a transverse section taken upon the line 4—4 of Figure 1.

Referring now to the drawings in detail wherein like numerals of reference indicate corresponding parts throughout the several views, there is shown an open frame formed of the side rails 1 and 2 and end rails 3 and 4. As is shown in Figure 2, the side rails are of greater depth than the end rails 3 and 4 the top edges of the four rails, however, being in the same plane.

Extending between the side rails 1 and 2 and connected thereto a slight distance inwardly of the ends thereof, are cross bars 5

the top edge of each of which is in the same plane as the lower edge of the adjacent end rail while the lower edge of each of the cross bars 5 is flush with the lower edge of the side rails 1 and 2. Revolvably mounted between the side rails 1 and 2, between the outer face of each cross bar 5 and the end edge of the side rails, are roller members 6.

Formed longitudinally of the inner face of each of the side rails 1 and 2, is a groove 7 which is substantially in alignment with the lower edge of the end rails 3 and 4 and passes over the top edge of the connecting bars 5. Secured along the lower portion of the inner face of each of the side rails 1 and 2 is a bar 8 having the top edge thereof flush with the lower side of the slot 7 and further having an inwardly extending flange 9 extending throughout its length.

Extending longitudinally of the frame and connecting the cross bars 5, is a pair of spaced parallel bar members 10, these bars being of substantially the same height as the cross bars 5 as shown in Figure 4.

Extending longitudinally of and along the inner face of each of the side rails 1 and 2, is a fabric belt 11 which belt lies upon the adjacent bar 8 and flange 9 thereof, and has one side edge positioned in the adjacent groove 7 of the side rail. This belt on each side of the frame, has its ends extended beyond and over the roller member 6 at each end of the frame and the ends of each belt are brought back beneath the frame and secured to one of a pair of cross bars 12 and 13. These cross bars 12 and 13 extend transversely beneath the frame and beneath the longitudinally extending bars 10, and each has secured thereto a pair of cleats or guide members 14. As is shown in Figure 3 these guide members or cleats 14 are so arranged upon their supporting bars 12 and 13 that one cleat 14 carried by the bar 12 will be positioned upon one side of the bar 10 in opposition to a cleat 14 carried upon the other bar 13 which is positioned upon the other side of the same bar 10. Securing straps 15 are passed about the bars 12 and 13 to draw the same together primarily for the purpose of tightening the belt or strap 11.

At the same time these securing straps 15 hold the cross bars 12 and 13 in such a manner that the same can be moved as a single unit, the spaced cleats 14 of the two bars acting as guide members upon both sides of the longitudinally extending bars 10.

Extending transversely of the frame between the side rails 1 and 2, above the slot 7, is a plurality of roller members 16, each of which members has a trunnion 17 in the 5 end thereof, which trunnion is extended into the adjacent side rail. Each of the roller members 16 has secured to one end thereof a toothed wheel 18 and, as is clearly shown in Figures 1 and 2, these toothed wheels alter- 10 nate with the wheelless ends of the rollers, placing the wheeled end of one roller next to the wheelless end of the adjacent roller. The wheelless ends of the rollers 18 are slightly reduced in diameter as indicated at 15 19 thus making it possible for a closer positioning of the rollers 16 for, as is shown the toothed wheels extend into these reduced portions 19.

As is clearly shown in Figures 2 and 4, 20 the toothed wheels bear against and bite into the fabric belt 11 and it will be readily seen that upon shifting the transverse bars 12 and 13 longitudinally of the frame, the belt 11 will be caused to pass about their rollers 11 will be caused to pass about their rollers 25 6 beneath the toothed wheels 18 causing these wheels to revolve and consequently revolving the rollers upon which they are carried.

Fitted over and secured to the frame 30 which is composed of the rails 1, 2, 3 and 4, is a top frame structure formed of the side and end rails 20, 21, 22 and 23. The rails 22 and 23 form the end rails of the frame and these rails are provided with vertical 35 grooves upon their inner faces to receive the longitudinally extending egg spacing strips 24.

As shown these egg spacing strips 24 extend downwardly through the slots in the 40 end rails 22 and 23 of the upper frame and

rest upon the end rails 3 and 4 of the main frame structure of the tray. The spacing strips are so positioned above the roller members 16 as to bring the apertures 25 which are formed through the strips substantially in alignment with the longitudinal axis of the eggs when the same are laid upon the roller members.

From the foregoing description it will be readily seen that the egg turning tray here- 45 in described, will give efficient and durable service, as all of the eggs placed therein can be easily turned by simply moving the connected cross bars 12 and 13 longitudinally of the frame. Further than this a positive 50 contact is made with all of the toothed wheels 18 so that all of the rollers will be 55 sure to turn when the belts are moved.

Having thus described my invention what I claim is:—

An incubator egg turner tray of the character described, comprising a frame, transverse substantially parallel egg supporting rollers mounted therein, substantially parallel longitudinally extending guide bars in 60 said frame beneath said rollers, a flexible belt extending longitudinally of each side of said frame beneath the ends of said rollers, means carried upon the ends of said rollers and contacting with said belts for revolution 65 thereof, a pair of transversely extending members lying beneath said guide bars and having the ends of said belts secured thereto, means carried by said members and engaging said bars for guiding the members 70 therealong; and adjustable securing elements connecting said pair of members together.

In testimony whereof, I affix my signature hereto.

ERNST W. NELSON.
